SHOE

Howard M. Goldberg, 1348 Grand Concourse,
Bronx, N.Y.

Filed Sept. 24, 1959, Ser. No. 842,089
1 Claim. (Cl. 36—2.5)

This invention relates to a shoe.

It is particularly desirable for the toes of a human foot to assume a flat position, i.e., parallel to the ground, when a person's weight is placed on the foot. This tends to maintain a normal foot in good condition and to aid in correcting orthopedic defects. However, a conventional shoe, due to its manner of construction, inhibits the desirable flat stance of a foot. When a shoe is lasted, the outsole is placed on the upturned curved bottom of the last and thereafter the flexible but inelastic upper is secured thereto, the upper conventionally being stretched tightly across the top of the last so that in the finished shoe, the outsole curves upwardly in the toe region, i.e., the front of the shoe. Due to this method of manufacture, as a human foot assumes weight, it must, before the toes will take on a flat position, stretch the upper in order to force the toe of the shoe downwardly against the ground. This resistance to the assumption of a flat stance is an unnatural restriction on the foot, tending to cause orthopedic defects and preventing orthopedic defects from being remedied.

It is an object of the present invention to provide a shoe which avoids the foregoing difficulty.

More particularly, it is an object of my invention to provide a shoe which minimizes the resistance offered to the assumption of a flat stance by a human foot when weight is placed thereon.

It is another object of the present invention to provide a shoe of the character described which is only slightly modified from a conventional shoe, this modification being such that it can be made at but a slight additional cost on conventional lasts.

It is another object of my invention to provide a shoe of the character described which lends itself to everyday methods of shoe manufacture on standard shoe making machines.

It is another object of my invention to provide a shoe of the character described in which the modification pursuant to my invention does not make the shoe unsightly or ungainly.

It is another object of my invention to provide a shoe of the character described in which the modification is not apparent, seeming to be merely a variation in the shoe design.

It is another object of my invention to provide a shoe of the character described which permits the wearer's toes to flex up and down with comparative freedom.

It is another object of my invention to provide a shoe of the character described which can be made in standard sizes, shapes and styles so that expensive molding and casting of individual orthopedic appliances can be eliminated.

It is another object of my invention to provide a shoe of the character described which is simple and inexpensive to make, is durable in construction, constitutes relatively few additional parts, and is, withal, attractive.

Other objects of my invention in part will be obvious and in part will be pointed out hereinafter.

My invention accordingly consists in the features of construction, combinations of elements and arrangements of parts which will be exemplified in the shoe hereinafter described and of which the scope of application will be indicated in the appended claim.

In the accompanying drawings in which is shown one of the various possible embodiments of my invention,

2

FIG. 1 is a front perspective view of a shoe made in accordance with my invention, the toe box being cut away to better see the modification which constitutes my invention; and

5 FIG. 2 is a side view of said shoe.

Although my invention can be embodied in any conventional shoe construction, I have, by way of example, shown the same as incorporated in a "McKay welt" shoe 10. Said shoe includes an upper 12 and lining 14 for said upper. The upper is made of the regular sheet material, e.g., leather or fabric, that is flexible but inelastic, that is to say, unyielding. The shoe further includes an outsole 16, a midsole 18, a filler 20 and an insole 22, all of conventional construction. The various parts of the shoe 15 are secured to one another in the usual manner as by last tacks 24 which fasten the inturned edges of the upper to the insole, a McKay seam 26 uniting the insole and upper to the midsole, and a lock-stitch 28 connecting the outsole to the midsole. It will be appreciated that up to 20 this point I have described nothing other than a conventional McKay welt shoe.

My invention consists in so modifying the upper 12 and the lining 14, which forms a part thereof, that from the tip of the toe of the shoe back to the region of the 25 cuboid 30 of a human foot in the shoe, the upper is able to experience movement in a vertical direction relative to the sole, the latter jointly including the outsole, insole, midsole and filler. In a conventional shoe, no such relative movement can take place. However, in a shoe embodying the present invention, such movement is per-

30 mitted by virtue of a suitable horizontal split in the upper starting at one side of the shoe in the region of the cuboid, running forwardly to and around the tip of the shoe and then back to approximately the same region 35 on the opposite side of the shoe. This split can be fashioned by actually forming such a slit in the material of the upper itself or by leaving a space between the lower edge of the upper and the sole. It further will be appreciated that when the upper actually is physically split, 40 that is to say constitutes a non-resilient, i.e., non-stretchable, part attached to the sole, and a similar part overlying the foot, the horizontal split should be located in the side wall of the upper, i.e., the vertical side part of the upper near, e.g., within about one-half inch, of the welt 32.

45 Moreover, my invention embraces the utilization at the split of an elongated member, e.g., a strip, that is resilient in at least a direction transverse of its length (vertical when the strip is in place) and that bridges the 50 space between the edges of the split. This member serves multiple purposes, e.g., it prevents the upper from flapping loosely, maintains a pleasing appearance, ensures a proper fit and offers a slight resistance to flexion of the forepart of the wearer's foot.

55 In the form of my invention specifically shown in FIG. 1, it will be observed that the lower edge of the upper from approximately the region of the cuboid bone forwardly on both sides of the shoe is spaced above the welt. I have used the term "upper" at this part of the specification to refer to the material which is conventionally used

60 in a shoe, e.g., the leather or fabric, although in the earlier portion of this specification I have used the term "upper" in a different sense to include both such material and the resilient strip. From this point forwardly, the term "non-yieldable portion of the upper" will refer to that part 65 of the upper which is made of conventional material, e.g., leather or fabric; the term "yieldable portion of the upper" will refer to the resilient strip, and the term "upper" will refer to the combination of the two.

70 Secured to the lower edge zone of the non-yieldable portion of the upper is a strip 34 of resilient material constituting the yieldable portion of the upper. Said strip

is narrow and elongated. It runs along both sides of the shoe and around the tip, extending from the region of the cuboid bone at one side of the shoe to the region of the cuboid at the other side of the shoe and bridges the slit between the sole and the lower edge zone of the non-yieldable portion of the upper. Suitable means is used to secure these two portions of the upper to one another. Although cement may be employed for this purpose, I prefer to connect said two portions to one another with a line of stitching 36 that extends through the non-yieldable portion of the upper, the yieldable portion of the upper and the lining 14, in turn, the upper edge zone of said yieldable portion of the upper, i.e., the strip, being sandwiched between the lining and the non-yieldable portion of the upper. The strip thus in effect constitutes the lower part of the upper, and the lower edge zone of said strip is secured to the insole by the tacks 24 and to the midsole by the McKay seam 26. Thereby this strip resiliently holds the non-yieldable portion of the upper to the sole of the shoe, and yet, at the same time, permits relative vertical movement between the two. The material of the strip is elastic transversely, i.e., vertically, preferably being fabricated from cloth woven or knitted with elastic threads such as the usual stretch material found in ladies' foundation garments, i.e., "power" mesh.

If desired, I also may employ a decorative strip 38 to conceal the raw lower edge of the non-yieldable portion of the upper, said decorative strip being held in place by the line of stitching 36 and by an additional line of stitching 40 below the stitching 36.

I have found that the presence of the resilient elastic strip at a slit in the otherwise inelastic upper, which slit extends deeply into the sides of the upper and around the tip of the shoe and is located in a substantially horizontal plane permits the sole readily to be forced to a

suitably flat position from the base of the metatarsals forwardly, whereby the metatarsal and phalangeal bones of the human foot in the shoe take on a flat stance when the foot assumes weight; the resistance offered by the upper to such straightening of the sole is comparatively slight and indeed is somewhat beneficial in that it affords exercise by slight resistance to flexing of the foot.

It thus will be seen that I have provided a shoe which accomplishes the several objects of my invention and is well adapted to meet the conditions of practical use.

As various possible embodiments might be made of the above invention, and as various changes might be made in the embodiment above set forth, it is to be understood that all matter described herein or shown in the accompanying drawings is to be interpreted as illustrative and not in a limiting sense.

Having thus described my invention, I claim as new and desire to secure by Letters Patent:

A shoe having a flexible inelastic upper, a sole to which the upper is secured, and a horizontally elongated strip of flexible vertically elastic material extending between the sole and the upper from the shank area of one side of the shoe to the shank area of the other side of the shoe.
